UNITED STATES PATENT OFFICE.

CHARLES T. WITTSTEIN, OF NEWARK, NEW JERSEY.

PHONOGRAPH CABINET.

Application filed June 6, 1921. Serial No. 475,266.

This invention relates in general to phonograph cabinets, and more particularly to the projection and amplification of sound reproduced therein, one object of the invention being to provide an improved construction for projecting the sound upwardly and outwardly above the motor and tone arm supporting board or partition of the cabinet, and improve the projecting and amplifying 10 of the sound and the quality of the tone.

Another object of the invention is to provide a cabinet having a horn-like recess above the motor supporting partition, a portion of the walls of said recess being formed 15 by said motor supporting partition and the remainder of said walls being formed by a structure having a configuration similar to a half horn formed by dividing a horn on its longitudinal axis mounted on or forming 20 a continuation of said motor board, means being provided for admitting the sound from the tone arm of the instrument into the inner end of said recess, whereby the said horn-like recess amplifies and projects 25 the sound outwardly above said motor board.

Other objects of the invention are to provide a construction whereby the sound from the tone arm is divided, a portion of it being projected upwardly over the motor board 30 and a portion being projected downwardly and outwardly beneath the said motor board or partition; and to provide such a construction wherein horn-like recesses are provided both above and below said motor 35 board so that the two recesses serve in effect as one large horn with the reproducing mechanism in the center thereof.

Further objects of the invention are to provide a phonograph cabinet having a 40 movable cover mounted above the motor board, and adapted in one position to enclose the reproducing mechanism and in another position to cooperate with the tone arm and serve as a horn for projecting the sound; to 45 provide a cabinet having a horn comprising a throat portion connected at one end to the tone arm and opening at the other end upwardly through the motor board, and another or bell portion comprising substantially a half horn connected at its small end to said throat portion and cooperating with 50 said motor board to form a horn-like recess above the motor board to project the sound from said tone arm; to provide a cabinet having a movable cover of a configuration 55 similar to a half horn formed by dividing a

horn on its longitudinal axis; said cover being mounted on said motor board and in one position forming a continuation of the same to form a horn-like recess, the said cover in another position serving to enclose the reproducing mechanism; and to obtain other results and advantages as will be brought out by the following description.

Referring to the accompanying drawings, 60 in which like numerals of reference indicate the same parts throughout the several views,

Figure 1 is a fragmentary vertical sectional view through the upper portion of a phonograph cabinet constructed in accordance with my invention showing the cover in closed position;

Figure 2 is a similar view showing the cover in open position for access to the reproducing mechanism, and for projecting 75 and amplifying the sound;

Figure 3 is a horizontal sectional view taken on the line 3—3 of Figure 2;

Figure 4 is a front elevation on a reduced scale of the invention shown in Figures 1—3 80 showing the cover in a closed position, as shown in Figure 1;

Figure 5 is a view similar to Figure 4 showing the cover in an open position, as shown in Figure 2;

Figure 6 is a view similar to Figure 1 showing a modified form of my invention in which the sound is projected both above and below the motor board, the horn portion as shown in Figure 2 being fixed with relation to the cabinet and an additional movable cover similar to that shown in Figure 1 being utilized for enclosing the reproducing mechanism;

Figure 7 is a front elevation on a reduced 95 scale of the invention shown in Figure 6 with the cover in an open position;

Figure 8 is a view similar to Figure 6 showing a modified construction of the horn beneath the motor board;

Figure 9 is a transverse sectional view taken on the line 9—9 of Figure 8;

Figure 10 is a view similar to Figure 2 showing another modified form of my invention, and

Figure 11 is a front elevation of the construction shown in Figure 10.

In the embodiment of my invention shown on the drawings, the reference character A designates the body portion of the cabinet 110 and the reference character B the motor board or supporting partition for the motor

C which is diagrammatically illustrated. Above the partition B the cabinet is formed with a hollow substantially rectangular extension D which is preferably built into the cabinet A the said extension being formed at the front thereof with an opening E in which is pivotally mounted on horizontal pivots 1 the swinging cover 2. The cover 2 has a configuration similar to a half horn 10 which would be formed by dividing a horn on its longitudinal axis, the large end or mouth 3 of the cover being substantially semi-circular in shape and of a diameter slightly greater than that of the opening E 15 in the extension D. The opening E in the extension D is semi-circular and the cover 2 is adapted to swing about the horizontal pivots 1 so that at one position, as shown in Figure 1, the front end or mouth 3 of the 20 horn like cover 2 rests upon the partition B while the small or throat end 4 thereof is positioned adjacent the top of the opening E. When in this position the cover 2 cooperates with the extension D to enclose the 25 turntable 5 and tone arm 6, the cover being formed at its sides with an extension 7 which extends around the throat end 4 of the cover so as to close the opening E when the cover is in closed position, as shown in Figure 1. 30 In the other position as the cover 2 swings about the pivots 1 it moves into the extension D and the sides and throat end 4 thereof rest upon the partition B, as shown in Figure 2.

35 A throat 8, which can be conveniently formed of cast metal, is mounted on the partition B and is connected at one end 9 thereof with the tone arm 6, the tone arm being swiveled over the end 9 of the throat in any 40 desired manner as indicated at 10. The throat projects downwardly beneath the partition B and the end 10 thereof is curved upwardly and opens through the partition B, the throat increasing in size from the end 9 thereof to the end 10. When the cover 2 is swung into the extension D of the cabinet the throat end 4 thereof rests upon the edges of the end 10 of the throat 8, as shown in Figures 2 and 3, so that the walls of the cover 50 2 form a continuation of the throat. It will thus be seen that with the side edges of the cover 2 resting on the partition B, as shown in Figures 2 and 5 a horn-like recess is formed above the partition B, the said partition forming a portion of the walls of the 55 said horn-like recess and the cover 2 forming the other portion of the walls in substantial continuation of the partition B. The sound issuing from the tone arm 6 is thus directed 60 through the throat 8 upwardly into the horn-like recess and is amplified and projected outwardly by the cover 2 and partition B which form in effect a horn.

65 The pivots 1 may be of any desired construction, and for the purpose of illustra-

tion, in Figure 3 I have shown the sides of the cover formed with studs 11 which rotate in bearing sockets 12 mounted in the sides of the extension D.

In Figures 6 and 7 I have shown a modified form of my invention in which the sound from the tone arm is divided, a portion of it being projected upwardly over the partition B and the other portion thereof being projected downwardly beneath the partition B. In this form of the invention the horn-like recess above the partition B is formed by the said partition and a member 13 of a configuration similar to a half horn, an additional swinging cover 14 which operates similarly to the cover 1, being provided for enclosing the turntable 5 and tone arm 6. In Figure 6 the cover is shown in a closed position by solid lines and in an open position by dotted lines. The throat 15 in this form of my invention has one end thereof connected to the tone arm 6, as at 16, the other end of the throat being bifurcated, the arm 17 thereof projecting upwardly through the partition B and the arm 18 thereof being connected to a horn 19 arranged below the partition B and opening through the front of the cabinet, as indicated at 20, in the usual manner. With this construction the sound from the tone arm passes through the throat 15 and is divided so that a portion thereof is projected through the horn-like recess formed by the member 13 and the partition B and the other portion thereof is projected through the horn 19.

In both of the constructions shown in Figures 1-5 inclusive and Figures 6 and 7, the sound being projected over the tone arm and turntable 5 tends to reduce the surface noise incident to the operation of the needle upon the record, and the projection and amplification of the sound is greatly improved and the quality of the tone enhanced. In the constructions shown in Figures 6 and 7 the reproducing mechanism is arranged between two horns so as to more thoroughly eliminate the surface noises from the projected sound. In this construction also the volume of sound is greatly increased due to the separate amplification of the sound through two horns. The construction shown in Figures 1-5 inclusive also has the advantages that the horn is located above the reproducing mechanism so that more space is available for the storage of records, if desired.

In Figures 8 and 9 I have shown a construction substantially identical with that shown in Figures 6 and 7 except that the partition B serves as a portion of the walls of both the upper horn and the lower horn. The lower horn 21 is shown as substantially rectangular in cross-section, see Figure 9, the upper wall 22 thereof being directed against the underside of the partition B, as shown

in Figure 8. It will thus be seen that the turntable 5 and tone arm 6 are mounted substantially in the center of a large horn which is formed by the walls of the upper horn 13 and the lower horn 21, the side walls of the said arms being substantially a continuation of each other with the partition B interposed between them.

Figures 10 and 11 illustrate another modification of my invention in which the cover 23 is pivotally mounted at 24 similarly to the cover 2 and is formed with a transverse partition 25 which terminates in a flat portion 26 adapted to engage the upturned end 27 of the tone arm 28, when the cover is thrown into an open position as shown by solid lines in Figure 10. The flat portion 26 is formed with an opening 29 which registers with the end of the tone arm 28, and it will be seen that the sound issuing from the tone arm will pass through the opening 29 through the horn-like passage formed by the walls of the cover 23 and the transverse partition 25. The tone arm is preferably swiveled as at 30 in axial alinement with the opening 29 so that the end of the tone arm always registers with the said opening in all positions of the tone arm. The cover 23 thus serves as a horn, and after the sound is projected beyond the partition 25 the partition B cooperates with the cover 23 as a portion of the walls of the horn to further project and amplify the sound.

While I have shown and described several possible embodiments of my invention, it will be understood that this is for the purpose of illustrating the principles thereof only, and that many modifications and changes can be made in the detail construction of my invention without departing from the spirit or scope thereof. Therefore, I do not desire to be understood as limiting myself except as required by the following claims when construed in the light of the prior art.

Having thus described the invention, what I claim is:

1. In a phonograph cabinet, the combination with a body portion providing a chamber and means for mounting sound reproducing mechanism in said chamber, of a movable member which in one position closes said chamber and in another position

cooperates with it to form an outwardly-opening horn-like recess, and means for discharging sound from the sound reproducing mechanism through said horn-like recess. 55

2. In a phonograph cabinet, the combination with a body portion having a partition forming a wall of a chamber and adapted 60 to support sound reproducing mechanism in said chamber, of a movable member which in one position closes said chamber and in another position cooperates with said partition to form an outwardly opening horn-like recess, and means for discharging sound from the sound reproducing mechanism through said horn-like recess. 65

3. In a phonograph cabinet, the combination of an extension and a partition forming a chamber for sound reproducing mechanism, a movable member cooperating with said extension and in one position closing said chamber and in another position forming an outwardly opening horn-like recess, 75 and means for discharging sound from the sound reproducing mechanism through said horn-like recess. 70

4. In a phonograph cabinet the combination with a body portion having a partition 80 therein, a hollow extension above said partition formed with an open side, and sound reproducing mechanism including a tone arm which is mounted on said partition, of a movable cover above said partition adapted in one position to close said opening of the said extension to enclose the said mechanism and in another position to move into said extension to open said side thereof, said cover in said second-mentioned position serving as a horn to project sound from said tone arm outwardly through said open side of the extension. 85

5. A phonograph cabinet including a body portion, a sound reproducing mechanism support, a fixed portion projecting upwardly above said mechanism support, a cover movable into and out of said fixed portion to cooperate therewith to respectively uncover and enclose said mechanism support, and means for transmitting sound from said reproducing mechanism into the space between said cover and said mechanism support when the cover is in said first-mentioned position. 90 95 100

CHARLES T. WITTSTEIN.
